US00D763520S

(12) **United States Design Patent**
Runyan

(10) **Patent No.:** **US D763,520 S**
(b4) **Date of Patent:** **** Aug. 9, 2016**

(54) **WASTE COLLECTION DEVICE**

- (71) Applicant: **Fred Runyan**, Novato, CA (US)
(72) Inventor: **Fred Runyan**, Novato, CA (US)
(**) Term: **15 Years**
(21) Appl. No.: **29/533,633**
(22) Filed: **Jul. 20, 2015**
(51) LOC (10) Cl. **30-99**
(52) U.S. Cl.

Primary Examiner — Susan Moon Lee(74) *Attorney, Agent, or Firm* — Steven A. Nielsen;
www.NielsenPatents.com(57) **CLAIM**

The ornamental design for a waste collection device, as shown and described herein.

DESCRIPTION

FIG. 1 is a top and side perspective view of a waste collection device showing my new design;
FIG. 2 is a front view thereof;
FIG. 3 is a back view thereof;
FIG. 4 is a left side view thereof;
FIG. 5 is a right side view thereof;
FIG. 6 is a top view thereof; and,
FIG. 7 is a bottom view thereof.
